(57) **CLAIM**

I claim the ornamental design for a cover for a cord lock mechanism, as shown and described.

DESCRIPTION

FIG. 1 is an isometric looking down on the top of the cover.

FIG. 2 is a top plan view of the cover.

FIG. 3 is a front elevation of the cover.

FIG. 4 is a bottom plan view of the cover.

FIG. 5 is a rear elevation of the cover having been inverted.

FIG. 6 is a left side elevation of the cover having been inverted.

FIG. 7 is a right side elevation of the cover having been inverted; and,

FIG. 8 is an isometric showing the cover connected with a cord lock mechanism in a cellular shade product which is shown in dashed lines and does not form part of the design.
